[57] CLAIM

The ornamental design for a check reader, as shown and described.

DESCRIPTION

FIG. 1 is a front elevational view of a check reader,

illustrating my new design;

FIG. 2 is a left side elevation of the check reader of FIG. 1;
FIG. 3 is a rear elevation of the check reader shown in FIG. 1;

FIG. 4 is a right side elevation of the check reader shown in FIG. 1;

FIG. 5 is a top plan view of the check reader shown in FIG. 1;

FIG. 6 is a bottom view of the check reader shown in FIG. 1;

FIG. 7 is a perspective view of the embodiment shown in FIG. 1;

FIG. 8 is a front elevational view of an alternate embodiment of the check reader in accordance with the invention;

FIG. 9 is a left side elevation of the check reader of FIG. 8;

FIG. 10 is a rear elevation of the check reader shown in FIG. 8;

FIG. 11 is a right side elevation of the check reader shown in FIG. 8;

FIG. 12 is a top plan view of the check reader shown in FIG. 8;

FIG. 13 is a bottom view of the check reader shown in FIG. 8; and,

FIG. 14 is a perspective view of the embodiment shown in FIG. 8.
